UNITED STATES PATENT OFFICE

CHARLES S. BROWN, OF SYRACUSE, NEW YORK

FENCE POST CONSTRUCTION

Application filed June 9, 1931. Serial No. 543,154.

This invention has for its object a metal fence post which is particularly simple and economical to manufacture, and also a particularly simple, economical and efficient 5 means for readily attaching the wires of the fence to the post.

The invention consists in the novel features and in the combinations and constructions hereinafter set forth and claimed.

10 In describing this invention, reference is had to the accompanying drawing in which like characters designate corresponding parts in all the views.

Figure 1 is a fragmentary elevation of a 15 post embodying my invention, the contiguous portions of the wires of the fence being shown.

Figure 2 is a sectional view on line 2—2, Figure 1.

20 Figure 3 is a fragmentary elevation of one form of wire tying member.

Figure 4 is an end view of parts seen in Figure 3.

25 Figure 5 is a fragmentary elevation of a slightly modified form of wire tying member.

Figure 6 is an edge view of the wire tying member shown in Figure 5.

This fence post comprises generally, an upper 30 right metal portion having a lengthwise slot opening through opposite sides and one end thereof, and a member for tying the wires to the post slideable into the slot and including a strip having portions extending on opposite sides of the wall of the post adjacent the slot, one of said portions being formed interlocked with the post, and the other of said portions having wire passages for receiving and binding the wires to the post.

40 1 designates the post, which is preferably hollow and tubular, it being here shown as circular in cross section, the post being split lengthwise to provide a lengthwise slot 2.

45 One end of the post is spread laterally into a position where it is located in a plane tangent to the circular portion of the post diametrically opposite the slot 2 thereby providing a base or blade 3 for entering the ground.

50 4 designates a wire tying member consisting of a strip movable endwise into the slot

2, the strip being formed with tongues 5 on one side of its median portion 6, that is, the portion in the slot of the post, which tongues are deflected in opposite directions to interlock with the post to prevent withdrawal of the tying member laterally out of the slot.

In Figure 2, the tongues 5 are shown as so deflected and as located on the interior of the post. The tying member strip is also provided with tongues 7 on the exterior of the post, these tongues being separated by slots 8 which have enlargements 9 at the inner ends of the slots forming wire receiving passages.

The slots 8 are of less width than the diameter of the wire and hence, by deflecting 60 adjacent tongues 7 in opposite directions, as shown in the upper part of Figures 1 and 2, or deflecting adjacent tongues 7 out of alignment, the wire can be passed into the enlargements 65 9 by a lateral movement thereof, as distinguished from a threading or endwise movement, by inclining the wire out of the horizontal, as indicated in dotted lines at A, Figure 1.

Figure 2 is a sectional view on line 2—2, Figure 1. After the wire has been inserted, the 75 tongues may be again deflected back into the plane of the strip, or the intermediate portion thereof which is located in the slot 2, as shown at 7^a, Figure 1. The tongues 5 and 7 are provided by slotting the strip transversely from opposite edges thereof, the slots terminating short of the intermediate portion of the strip, that is, the portion located in the slot 2 of the post.

Figure 3 is a fragmentary elevation of one form of wire tying member.

Figure 4 is an end view of parts seen in Figure 3.

Figure 5 is a fragmentary elevation of a slightly modified form of wire tying member.

Figure 6 is an edge view of the wire tying member shown in Figure 5.

This fence post comprises generally, an upper right metal portion having a lengthwise slot opening through opposite sides and one end thereof, and a member for tying the wires to the post slideable into the slot and including a strip having portions extending on opposite sides of the wall of the post adjacent the slot, one of said portions being formed interlocked with the post, and the other of said portions having wire passages for receiving and binding the wires to the post.

1 designates the post, which is preferably hollow and tubular, it being here shown as circular in cross section, the post being split lengthwise to provide a lengthwise slot 2.

One end of the post is spread laterally into a position where it is located in a plane tangent to the circular portion of the post diametrically opposite the slot 2 thereby providing a base or blade 3 for entering the ground.

4 designates a wire tying member consisting of a strip movable endwise into the slot

- ures 5 and 6 is furnished flat in rolls and the buyer can deflect the tongues 13 to interlock with the post and the tongues 14 to receive the wire after cutting off the desired length of the strip and before placing the strip in the post to receive the wires and for the purpose of facilitating the cutting off, the slots 11 and 12 are located in alinement leaving only a narrow portion to be cut.
- 10 In the form of the strip shown in Figures 3 and 4, the strip is furnished in any desired lengths with the tongues 5 and 7 deflected so that the strips are ready to be assembled in the post.
- 15 It is preferable to arrange the transverse slots out of alinement, as shown in Figure 3, in order to weaken the strip as little as possible by the formation of the transverse slots, or in order to leave as much stock as possible intervening between the slots 8 and 10.
- 20 This post is particularly economical and strong in construction, and owing to the wire tying strip, the wires can be readily tied to the post, and the tongues will hold the wires from slipping, particularly as the wire passages or enlargements 9 are small compared with the diameter of the wire, and the edges of the wall around the slot bind onto or dig into the wire, either when the tongues 7 are left deflected, as shown in Figure 2, and the upper part of Figure 1, or are straightened back into alinement with each other or into the plane of the strip, as shown at 7^a, Figure 1.
- 25 30 35 What I claim is:
1. A fence post comprising a tubular upright metal wall having a lengthwise slot, and a member for tying wires to the post comprising a strip insertable in the slot and extending lengthwise thereof and provided with means for interlocking with the inner side of the post adjacent the slot, the strip extending beyond the front face of the post adjacent the slot and provided with transverse slots extending inwardly from its outer edge and terminating short of the portion of the strip in the slot, said slots providing tongues, the slots having enlarged portions at their inner ends serving as wire receiving passages, whereby a wire is movable lengthwise into the enlarged portion when two adjacent tongues are deflected out of alinement.
  2. A fence post comprising a tubular upright metal wall having a lengthwise slot, and a member for tying wires to the post comprising a strip formed with transverse slots extending inwardly from the opposite edges thereof, the slots terminating short of the portion of the strip in the slot thereby providing tongues, the tongues along one side of the strip being deflectable out of the plane of the strip forming means for interlocking with the inner side of the post adjacent the lengthwise slot therein, and the slots on the outer side of the strip being provided with

enlargements at their inner ends constituting wire passages.

3. A fence post comprising a tubular upright metal wall having a lengthwise slot, a member for tying wires to the post comprising a strip formed with transverse slots extending inwardly from the opposite edges thereof, the slots terminating short of the portion of the strip in the slot of the post adjacent the slot in the post thereby providing tongues, the tongues along one side of the strip being deflectable out of the plane of the strip forming means for interlocking with the inner side of said wall, and the slots on the outer side of the strip being provided with enlargements at their inner ends constituting wire passages, the tongues on the outer side being deflectable out of alinement to permit the wires to be placed in the enlargements.

4. A fence post comprising a tubular upright, split longitudinally forming a lengthwise slot, a wire binding strip insertable in the slot through the upper end thereof and having tongues located on the inner side of the post and deflectable out of the plane of the strip for interlocking with the post, and tongues extending on the outside of the post and provided with wire passages between the bases of said tongues and with slots leading from the enlargements through the outer edge of said portion, the latter tongues being deflectable out of the plane of the strip for permitting the wires to be passed side-wise into said passages.

5. A fence post comprising upright metal body including a wall having a lengthwise slot opening through its opposite sides and a wire tying member comprising a strip insertable in the slot and extending lengthwise thereof and provided with means for interlocking with the rear side of said wall, the strip extending beyond the front face of said wall and being provided with transverse wire receiving slots extending inwardly from its outer edge and terminating short of the portion of the strip in the slot of the post, said slots providing tongues whereby a wire is movable lengthwise into the slot when two of the adjacent tongues are deflected out of alinement, and the tongues are tightened on the wire when the adjacent tongues are deflected toward alined positions.

In testimony whereof, I have hereunto signed my name, at Syracuse, in the county of Onondaga, and State of New York, this 29th day of May, 1931.
